Patented June 22, 1915.

UNITED STATES PATENT OFFICE.

HARRY T. HIPWELL, OF PITTSBURGH, PENNSYLVANIA.

FLASHLIGHT.

1,143,966.

Specification of Letters Patent. Patented June 22, 1915.

Application filed October 31, 1914. Serial No. 869,611.

To all whom it may concern:

Be it known that I, HARRY T. HIPWELL, a citizen of the United States, residing at N. S. Pittsburgh, in the county of Allegheny and State of Pennsylvania, have invented a new and useful Flashlight, of which the following is a specification.

The present invention appertains to electric flashlights, and aims to provide a novel and improved lens construction therefor, whereby the rays of light are condensed in order that they may be concentrated upon the object to be illuminated.

It is the object of this invention to provide an electric flashlight with a condensing lens in connection with the main lens, whereby the greater portion of the light rays will be concentrated in a strong pencil or stream of light of comparatively small cross sectional area, in order that the object to be illuminated may be illuminated with the greatest intensity, and in order that the light may be carried for a greater distance than is possible with the ordinary flashlight having a single lens.

Another object of the invention, is to provide novel means for assembling the lenses with the body or case of the flashlight.

It is also within the scope of the invention, to provide a lens structure of the nature indicated which will be comparatively simple and inexpensive in construction, which may be readily applied to ordinary flashlights, and which will be efficient and practical in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in its preferred embodiment in the accompanying drawing, wherein:—

Figure 1 is an elevation of an electric flashlight having the improved lens structure applied thereto, the lens structure and a portion of the flashlight being shown in section; Fig. 2 is a cross sectional view taken on the line 2—2 of Fig. 1.

In the drawing, the numeral 1 designates the hollow tubular body or case of the flash-

light, which incloses the battery or batteries 2, and which carries a suitable controlling switch 3.

A parabolical or cup-shaped reflector 4 is fitted within one end of the body 1, and is provided with an outturned rim or flange 5 seating against the end of the body, and with a central inwardly projecting threaded socket 6 for receiving the plug of the incandescent lamp 7. The lamp 7 is brought in circuit with the batteries 2, in any suitable manner, preferably through the medium of inclosed conductors 8 extending from the switch 3, one conductor being electrically connected to one pole of the batteries 2, while the other conductor is connected to the reflector 4, which is a conductor so as to be in electrical connection with the lamp 7. The lamp 7 contacts with the other pole of the batteries.

A ferrule 9 is secured upon that end of the body 1 which incloses the reflector 4, and is threaded to receive thereon, a ring 10. The ring 10 carries a funnel-shaped shell 11, which comprises the frusto-conical or flared body portion 12, having the reduced or spout portion 13 at its smallest end. The end of the reduced or spout portion 13 is provided with an inturned annular flange or lip 14 which is soldered or otherwise secured to the outer edge of the ring 10, whereby the ring 10 forms an extension for the spout portion 13. The frusto-conical or flared portion 12 of the shell 11 is provided at its largest end with an enlarged cylindrical portion or rim 15 which is threaded, and which has its edge inturned to provide an annular flange or lip 16.

The main lens 17, which is of plano-convexed form, has its marginal portion seated against the flange or lip 16, with the flat or plane face of the lens facing inwardly, and a threaded retaining ring 18 is threaded upon the rim 15 of the shell 11 and is provided at its outer edge with an inturned annular flange or lip 19 engaging the marginal portion of the lens 17 and clamping the same against the flange 16 of the shell 11. The lens 17 is of relatively large diameter.

Disposed within the spout 13—10 of the shell 11 is a condensing lens 20 of relatively small diameter, and preferably of plano-convexed form with its plane or flat face facing inwardly. The lens 20 is disposed within the ring 10 and seats against the flange 14 of the spout 13—10 whereby when

the ring or portion 10 of the spout is threaded onto the ferrule 9, both the flange 5 of the reflector 4 and the condensing lens 20 will be clamped against the corresponding end of the body 1. It will thus be noted that the shell 11 which is of funnel-shaped form, carries the main lens and its enlarged portion or rim, and carries the condensing lens 20 within its spout, the spout having an inner flange and being adapted to be threaded onto the end of the body to clamp the condensing lens as well as the reflector against the end of the body.

When the shell 11 containing the main and condensing lenses is applied to the body 1, and the switch 3 manipulated to light the incandescent lamp 7, the light rays in passing through the two lenses will provide a strong pencil or stream of light, which is adapted to illuminate the object with the greatest intensity, and which will extend for a considerably greater distance, than is possible with the ordinary single lens flashlight. The light rays passing through the two lenses will be refracted so as to collect the light rays into a relatively small stream. With the present device, therefore, the greater portion of the light rays are condensed in order that they may be concentrated upon the object to be illuminated, with the greatest possible or maximum illumination, and with the greatest carrying power.

The interior of the reflector 4 is preferably polished or otherwise treated to provide a mirror or highly reflective surface while the interior of the shell 11 is preferably blackened or darkened to avoid the reflection of light therein, it being noted that the condensing lens 20 is mounted within the spout of the shell 11 over the mouth of the reflector 4, while the main lens 17 is carried by the free portion of the shell 11 over the mouth thereof.

Having thus described the invention, what is claimed is:—

1. A flashlight comprising a body, a reflector fitting within one end thereof, a lamp mounted within the reflector, a condensing lens disposed over the mouth of the reflector, a shell detachably engaged over

the said end of the body and having means for holding the condensing lens and reflector in place, and a main lens carried by the free portion of the shell.

55

2. A flashlight comprising a body, a reflector fitting within one end thereof and having a flange seated against the said end of the body, a lamp disposed within the reflector, a condensing lens seated against the said flange of the reflector, a shell detachably engaged over the said end of the body and having an inner flange engaging the condensing lens for clamping the reflector flange and condensing lens against the end of the body, and a main lens carried by the free portion of the shell.

60

3. A flashlight comprising a body, a reflector fitting within one end thereof, a lamp disposed within the reflector, a funnel-shaped shell having its spout portion detachably engaged over the said end of the body, a relatively large main lens carried by the mouth portion of the shell, and a relatively small condensing lens disposed within the spout portion of the shell over the mouth of the reflector, the spout portion of the shell having means for holding the condensing lens and reflector in place against the end of the body.

65

4. A flashlight comprising a body, a reflector fitting within one end thereof and having a flange seated thereagainst, a lamp disposed within the reflector, a funnel-shaped shell having its spout portion detachably engaged over the said end of the body, a relatively large main lens carried by the mouth portion of the shell, and a relatively small condensing lens disposed within the spout portion of the shell and fitting over the mouth of the reflector, the spout portion of the shell having an inner flange engaging the condensing lens for holding the same and the reflector flange against the end of the body.

70

In testimony that I claim the foregoing as my own, I have hereto affixed my signature in the presence of two witnesses.

HARRY T. HIPWELL.
